UNITED STATES PATENT OFFICE.

GEORGE H. PEGRAM, OF NEW YORK, N. Y.

GUNBOAT.

1,281,413.

Specification of Letters Patent.

Patented Oct. 15, 1918.

Application filed April 14, 1917. Serial No. 161,943.

To all whom it may concern:

Be it known that I, GEORGE H. PEGRAM, a citizen of the United States, and resident of New York city, county of New York, and

5 State of New York, have invented an Improvement in Gunboats, of which the following is a specification.

My invention relates to gun-boats for coast defense, and is designed to provide 10 boats of shallow draft having suitable motive power and capable of carrying two naval guns of large caliber and adapted to be otherwise equipped with guns of smaller caliber, torpedo tubes, etc., as found desirable, the same providing a vessel of 15 comparatively inexpensive construction having a larger factor of safety against destruction than is now usual in naval vessels.

It is recognized that the present types of 20 battleships and cruisers have proven very vulnerable to attack, especially by torpedoes, and the enormous financial loss in the destruction of a large battleship or cruiser, makes the division of the same gun fire 25 equipment of such a ship into several separate units desirable. These large ships are moreover relatively weak against the explosive force of a torpedo on account of their shape, more particularly as to their length, 30 the force of the explosive tending to break the ship amidships similar to the action of a blow on a long beam. Such ships are also liable to self-destruction by grounding, as the hull cannot be lifted at one point without 35 breaking the plates or opening the seam.

In embodying my invention in practical form, I provide the ship with a circular or oval shape in plan which may be formed with an internal bracing construction sufficiently strong that the ship may be lifted 40 at any point of the circumference without injury, because of the great and practically uniform moment of resistance across the diameter in any direction. Instead of relying 45 upon heavy armor (which is now readily pierced), I divide the boat into a great number of water-tight compartments and provide for special immunity through the curved and inclined surfaces which tend to deflect 50 shots, and by reason of the low visibility which may be enhanced by provision to sink the boat for action to any desired degree, by flooding some of the compartments, to be later pumped out. By the radial girder and 55 other strong bracing of rolled girder shapes and plate construction, the explosion of a

torpedo is resisted in all points of attack, and the injury, if inflicted, effectually localized.

The boat is propelled by taking the water 60 in at the bow and discharging it at the stern through conduits or channels, the resistance of the bow wave and stern draft, which would be great in body of circular shape 65 propelled in the ordinary way, being thus reduced. Various known propelling appliances for moving water might be applied, but screw propellers are shown for illustration and are perhaps the most effective. Two screw propellers are used, one on each 70 side of the center of the boat and inclosed within the conduits of the structure, each one operating on a draft conduit or tube extending from the bow to the stern through which water is propelled. These draft conduits or tubes are preferably tapered from 75 near the middle to the ends in order to lessen friction; and in the tapered conduits are placed substantially balanced rudders for steering the boat. It is also obvious that 80 the ship can be steered by the relative operation of the two propellers in conjunction with or independently of the rudders. It is further obvious that the conduits may be flared at one end only.

85 A single tube might be used for small boats or in special constructions which would be without many of the advantages of the design shown in the drawings but would have some applicability in small boats and 90 special cases, as for instance, where great economy of space is desired.

The duplicating of parts for propelling and steering the boat and their protection from injury are special advantages of the 95 design.

My improved coast defense ship constitutes a floating battery having adequate motive power for self-propelling purposes, steering means, and preferably provided 100 with the general equipment of a large battleship in so far as is necessary for the lesser armament and motive power, such details however forming no part of my invention.

105 For the purpose of illustrating my invention, I have shown in the accompanying drawings the embodiment thereof which is at present preferred by me, since the same is in form to give satisfactory and reliable results, but it is to be understood that the 110 several features or structures of which my invention consists, can be variously ar-

ranged, organized and modified and that my invention is not limited to the precise arrangement and organization of the structures herein shown and described.

5 Referring to the drawings: Figure 1 shows a vertical longitudinal cross section of the boat on the plane $z-z$ of Fig. 3; Fig. 2 is a horizontal cross section on the plane $x-x$ of Fig. 1; Fig. 3 is a similar horizontal cross section on plane $y-y$ of Fig. 1; and Fig. 4 is a sectional plan of a modification.

A is the continuous steel plate bottom of the boat, and B is the continuous steel plate 15 lower deck on the entire hull of the boat. The bottom A and deck B are connected by a grillage of vertical plate webs a and b riveted between them and forming a very strong bottom of girder construction. Ex- 20 tending across the hull and through the grillage between the bottom plates A and deck plates B, I provide two conduits or tubes H, H, arranged substantially parallel at a distance apart and respectively upon 25 opposite sides of the center.

These conduits H flare or widen at the ends, as indicated; and said conduits may be stiffened by the vertical plates h in said flared or widened ends. At the ends these 30 conduits are provided with balanced rudders J, J, said rudders to be operated in any suitable manner, as is customary in ship construction. These conduits at their middle portions are preferably given an upward 35 curve as at I in which the screw propellers K are arranged, with their shafts extending obliquely upward through suitable stuffing boxes and connected with engines L, which may be of any suitable construction. These 40 propellers are preferably driven by independent Diesel engines using crude oil fuel, requiring no furnaces and reversible or having reverse gear m , but they may, if desired, be operated by turbines or electric turbine 45 drive, in which cases some of the outer compartments l may be employed for boiler room equipment. Such obvious and well-known appliances are not shown, as specifically they form no part of my invention. 50 The propellers K in the two conduits H, H, may be independently operated in the same or in opposite directions for the purpose of not only propelling the boat, but also to assist in rapidly turning it.

55 The general design of the ship in plan is circular or oval, the outer walls being vertical as at K'. These may be reinforced with armor plate P, if so desired; E is the upper or hurricane deck and is preferably 60 curved, rising to the center at which place the large turret G is fitted. The location of the turret is over the center of gravity of the boat. This hurricane deck is preferably provided with sufficient armored protection e to resist aerial bombs. C is a coni-

cal plate bulkhead, extending from the hurricane deck near the sides of the hull to the lower deck B, thereby separating the inner compartments d, d', and outer compartments l of the hull. D is the mezzanine deck. 70 F is the citadel and G the gun turret having a suitable complement of guns g according to usual practice in battleship design. The compartment N may be employed as a magazine. 75

The water-tight compartments l may be used for various purposes, some for torpedo tubes S, others for machinery, stores and quarters for the men when not in action, and still others may be flooded to aid submergence. In the case of these latter, sea cocks T may be employed to admit water and pumps t employed to discharge it, as required. 85

In respect to the compartments W in the hull at the bottom and formed by the grillage, the same may be connected in clusters by pipes w and employed for storage of oil fuel and for water ballast, as may be desirable. 90

In Fig. 1, the vessel is shown at its normal water line; but when in action, the vessel may be submerged by admitting water into the compartments until only approximately one half of the normal exposure of side walls 95 is provided; the extent of this submergence may, however, be varied to suit the conditions which have to be met.

Aside from the general construction of hull and equipment described, there may be 100 employed a mast O of light and strong construction preferably carried upon and rotating with the turret G so as not to interfere with the guns in action. This mast may be provided at its upper end with an observatory or fighting top O' whereby it constitutes a military mast. At its top, this mast is provided with a flag staff Q which also acts as a support for the upper end of a wireless antennæ equipment R, the lower end 110 being connected with the deck of the ship near its side. The cable for connecting the said wireless antennæ at the top is attached to a swivel support r journaled on the upper end of the flag staff, so that the mast may 115 rotate with the turret and at all times maintain a suitable connection with the wireless antennæ R.

It will now be apparent that I have devised a novel and useful construction which embodies the features of advantage enumerated as desirable, and while I have in the present instance shown and described the preferred embodiment thereof which has been found in practice to give satisfactory and reliable 120 results, it is to be understood that I do not restrict myself to the details, as the same are susceptible of modifications in various particulars without departing from the spirit or scope of the invention. 125 130

Having now described my invention, what I claim as new and desire to secure by Letters Patent, is:—

1. A gun boat of substantially circular form having the body portion formed with a central compartment surrounded by a plurality of radially walled water-tight compartments of large size having inclined upper walls extending from the upper portion 10 of the outer wall and sloping inwardly and downwardly and terminating adjacent to the bottom of the central compartment, a floor extending from the wall of the central compartment to the middle of the sloping upper portions of the water-tight compartments a gun turret arranged over the central compartment above the center of gravity of the boat, and propelling devices at the lower part of the boat for propelling it.
2. A gun boat having a circular shape in plan and with its bottom strengthened by a grillage of vertical plates, the space above the bottom divided by an inverted conical wall extending from the central portion of the bottom obliquely upward and terminating at the deck adjacent to the sides of the vessel to provide compartments on opposite sides of said inverted conical wall the space below the said conical wall divided into a plurality of water-tight compartments by radial division walls, and means for admitting water to a plurality of said last mentioned compartments and discharging it therefrom, combined with a gun turret arranged above the deck and adjacent to a vertical line through the center of gravity of the boat.
3. A gunboat of substantially circular shape in plan having a revolving gun turret 40 at its middle upper portion, propelling

means arranged at the lower part of the boat and adjacent to its central portion, and a military mast supported upon and rotating with the turret.

4. A gunboat of substantially circular shape in plan having an upwardly curved upper deck and a substantially flat bottom of grillage construction to give great strength, the space between the deck and bottom being provided with an inverted conical partition, central compartments within the boundary of the conical partition and outer compartments between the space below the conical partition and between it and the sides and bottom of the boat said space being divided by a plurality of radial division walls to provide a great number of radial compartments, and a gun turret arranged centrally above the inner compartments.

5. A gunboat having a substantially circular shape in plan and provided with an inverted conical division partition forming inner and outer compartments and a plurality of radial division plates for dividing the outer compartment into a large number of radial compartments, and means for admitting water to a portion of the radial compartments and discharging it therefrom at will, combined with a gun turret at its middle upper portion and substantially over the center of gravity, and propelling devices arranged at the lower part and protected by the radial compartments.

In testimony of which invention, I hereunto set my hand.

GEORGE H. PEGRAM.
